UNITED STATES PATENT OFFICE

JACK W. LEVI, OF CINCINNATI, OHIO, ASSIGNOR, BY MESNE ASSIGNMENTS, TO
STEWART S. COOPER, OF CINCINNATI, OHIO

AVIATOR'S HELMET

Application filed January 18, 1929. Serial No. 333,385.

My invention relates to aviators' helmets and to improvements in the construction thereof.

Aviators' helmets in the past have been close fitting and have had portions extending down at the ears, which completely cover them. An instructor of flying has to unfasten the parts of the helmet which fasten under the chin and pull up the sides whenever he wishes to hear what his pupil says. So too, the pupil has to unloosen and lift up the sides of his helmet whenever he wishes to hear what the instructor is saying. To avoid the frequent fastening and unfastening of the neck encircling portions of the helmet, aviators frequently leave their helmets unfastened, which permits the cold air encountered to frequently freeze their ears, and it also makes them much more often subject to deafness from the roar of the engine. Further, the ordinary aviators' helmet has no means for protecting the eyes of the aviator from the glare of the sun, and the sun frequently blinds him enough to increase the likelihood of accident, particularly when several planes are flying in close formation. Although a shade for the eyes in some lights is desirable, on dark days it is undesirable.

It is the object of my invention to provide a helmet which will have adjustable ear flaps which may be uncovered without the necessity of removing the helmet straps. Another object is the provision of the helmet body and ear flaps in such an arrangement that when closed down the flaps will form a double seal against the passage of the wind and sound. A still further object is the provision of a shield for the eyes which is so attached to the helmet that it may quickly be adjusted from a position shielding the eyes of the aviator, to a position in which it conforms to the shape of the helmet and does not shield the eyes or face.

I, also, have as an object the provision of a novel type of shield which reinforces the hel-

met along the line of attachment of the eye shield, but is opposed to and on the inner side of the helmet. Another object, is the provision of a quickly releasable neck fastener preferably formed of extensions of the helmet body.

The above and other objects to which reference will be made in the ensuing disclosure I accomplish by that certain combination and arrangement of parts of which I have shown a preferred modification.

Referring to the drawing:

Figure 1 is a side elevation of the helmet with a cut away portion at the front showing the inner construction of the helmet and with the eye shading portion down.

Figure 2 is a side elevation from the side opposite that from which Figure 1 is shown, with the eye shading portion bent back in non-light obstructing position.

Figure 3 is a sectional view taken along the lines 3—3 in Figure 2 showing the adjustable ear flap construction.

The helmet is made with a pair of matched pieces 1 forming the crown or top head covering portion. To the pieces 1, pieces 2 are stitched forming the side head covering portions of the helmet. One piece 2 has preferably an extension 3 which acts as a strap, being secured under the chin of the wearer to a buckle 4 fastened to an extension 5 extending down from the piece 2 on the side opposite that having the long extension 3. The aviator may quickly release the helmet by pulling down on the end of the extension 3.

At the front of the helmet I have stitched an eye shield 6 formed of arcuate shaped pieces enclosing a stiffener piece. The eye shield may, as indicated, be quickly bent up from the position shown in Figure 1 to the position 6a shown in Figure 2. An arcuate shaped guard 7 is also secured inside the helmet opposed to the eye shield.

In the portions of the helmet which cover the ears, I have cut circular openings and

have stitched on annular members 8 which form a ring around the opening extending up above the main surface of the helmet. The ear flaps 9 are secured at their upper 5 ends to the helmet, and have fasteners such as the snap fasteners 10 which engage the button fasteners 11 which are secured to the body of the helmet.

On the inner surface of the ear flaps I 10 have stitched annular members 12 of slightly larger extent than the members 8 so that when the flap is laid flat against the helmet, both members 8 and 12 will provide a double annular partition wall which will effectively 15 prevent either the passage of air or sound in under the ear flap.

When the aviator wishes to hear what another flyer says he unfastens the flap and raises it so that the sound may pass through 20 to his ear. When he has finished he secures the flap in position again covering his ear. I have also provided a loop 13 at the back of the head portion which will retain the strap of the aviator's goggles.

25 While in the foregoing specification I have gone into some detail in stating the specific construction of the helmet which I have described, there are many possible variations from the specific structure shown which will occur to those skilled in the art, without departing from the invention which I have disclosed.

Having thus described my invention what 30 I claim as new and desire to secure by Letters Patent is:

1. An aviator's helmet having orifices extending therethrough in the portions thereof lying over the ears of a wearer, and means 35 for detachably covering said orifices, said means comprising flaps secured along one edge and having means for fastening same to the body of the helmet along the opposite edges, said flaps having annular wind breaking members, and said helmet having 40 registering annular wind breaking members surrounding said orifices whereby double air seals are provided for precluding the passage of air under said flaps when same are closed.

45 2. An aviator's helmet having passages therethrough over the portions covering the ears of a wearer, annular ridges secured to and surrounding said passages, and adjustable ear flap pieces also having annular 50 ridges, said ridges constructed and arranged to form a double air seal for preventing the passage of air under said flaps.

55 3. An aviator's helmet having passages therethrough over the portions covering the ears of a wearer, annular ridges secured to and surrounding said passages, and adjustable ear flap pieces also having annular 60 ridges, said ridges constructed and arranged to form a double air seal for preventing the 65 passage of air under said flaps, and means

for securing said flaps against the outer surface of the helmet.

4. An aviator's helmet having passages extending through the sides of the helmet, flaps for covering said passages, means for fastening said flaps in covering position and means on said body and flaps for preventing the passage of air beneath said flaps when closed, said means comprising interfitting 70 complementary projections on said body and 75 said flaps surrounding said passages.
